UNITED STATES PATENT OFFICE.

EDWIN B. SMITH, OF MARION, INDIANA, ASSIGNOR TO MARION MACHINE, FOUNDRY & SUPPLY COMPANY, OF MARION, INDIANA, A CORPORATION.

CRUSHER.

Application filed March 22, 1924. Serial No. 701,091.

To all whom it may concern:

Be it known that I, EDWIN B. SMITH, a citizen of the United States, and a resident of Marion, county of Grant, and State of Indiana, have invented a certain new and useful Crusher; and I do hereby declare that the following is a full, clear, and exact description thereof, reference being had to the accompanying drawings, in which like numerals refer to like parts.

This invention relates to a crusher which is herein illustrated as of the single roll type.

The chief object of the invention is to construct a crusher which will have considerable flexibility and considerable capacity.

Another object of the invention is to construct and arrange the parts of the crusher in such a manner that the same may be readily removed for replacement or repair purposes and only those parts removed and renewed which require renewal.

The chief feature of the invention consists in the construction of the crusher in units and providing the respective units with suitable actuating means for actuating said units as a whole, but which permits said units to operate with considerable flexibility.

The full nature of the invention will be understood from the accompanying drawings and the following description and claims:

In the drawings, Fig. 1 is a top plan view of a crusher of the roll type embodying the features of the invention. Fig. 2 is a side elevational view thereof, parts being shown dotted. Fig. 3 is a transverse sectional view of a crusher unit roll and is taken on the line 3—3 of Fig. 2 and in the direction of the arrows. Fig. 4 is a plan view of one of the breaker plate units.

In the present invention the crusher is illustrated as of the roll type, and herein the same is shown composed of a plurality of crusher roll forming units. These roll forming units are herein shown suitably supported upon a common shaft, and so supported in the present instance that they operate simultaneously and have no relative movement with respect to each other. Associated with the unified roll is a unified breaker plate construction including a plurality of unit breaker plates, each mounted upon a common support and individually actuated to return to a predetermined normal position when subjected to unusual stress. The

advantage obtained by thus forming the breaker plate in units is that if the crusher operates upon coal of rather uniform size and attempts to operate at one portion upon a relatively larger size, that operating portion adjacent the larger size piece of coal will yield and permit the crusher to reduce the size of the larger sized coal. At the same time, however, the remainder of the crusher does not vary, therefore, and the normal crushing action is carried on simultaneously with this abnormal crushing action, reference being had to the reduction of an unusually large size piece of material to smaller sizes corresponding to the initial size of the normal run of the material. This feature of the invention permits the crusher to operate upon material which runs from relatively small to substantially any size within the capacity of the crusher and most expeditiously reduce the same to the desired final size, which, it will be apparent, gives the resultant crusher a capacity greater than the usual crushers, for the reason that all parts of the crusher are operating at all times and insures that the product discharged from the crusher is of substantially uniform size.

In the drawings 10 indicates a base having the sides 11 upstanding therefrom and provided with a pair of bearings 12 and 13 therein. Caps 14 and 15 rotatably support shafts 16 and 17 in said bearings. Herein the shaft 17 supports a power pulley 18 at an extended end, while upon its opposite extended end it carries a suitable gear wheel 19 adapted to mesh with a similar wheel 20 upon the extended end of the shaft 16. The sides 11 also are provided with another bearing 21 in the upper portion, and the caps 22 secure a shaft or pivot 23 therein, which herein is shown as a stationary pivot, since set screw 24 is provided.

The sides 11 of the base are connected by an inclined plate 25 and these together with the breaker plate construction indicated generally by the numeral 26 form a hopper, the latter also forming a portion of the crushing surface. Positioned at the throat of the hopper thus formed and supported upon the shaft 16 and suitably secured thereto and actuated thereby in the present instance by means of the keys 27, are the crushing unit rolls 28, which are provided with a key slot 29, as shown. Each crushing unit roll upon

its peripheral surface is provided with a plurality, and herein three are illustrated, of rows of small crushing teeth 30. At spaced distances about the periphery and medianly positioned on the roll are a plurality of larger teeth 31. The individual rolls are so positioned with respect to each other, see Fig. 1, that the larger teeth 31 of adjacent rolls are in staggered relation. 10 This construction secures an agitating or stirring of the entire mass passing through the throat of the crusher by reason of the intermittent passage therethrough of the alternately spaced and staggered larger teeth. 15 These teeth also assist in the crushing action.

The breaker plate construction 26 includes a plurality of similar units, and, therefore, a description of one will suffice for them all. Each breaker plate unit includes at one end 20 a bearing 32 which is adapted to embrace the common pivot 23 previously described and pivotally support the unit breaker plate. Each breaker plate is herein shown provided near its upper end with a single and medianly positioned tooth 33 somewhat larger than another pair of teeth 34 also medianly but lower positioned. These teeth are indicated by the numeral 34. Beneath the pair of teeth 34, there is provided another set or 25 row of teeth 35 somewhat smaller than the last mentioned teeth, and herein are shown as three in number. The breaker plate unit as illustrated particularly in Figs. 1 and 2 is recessed as at 36 to receive a chilled steel 30 shoe 37, which chilled steel shoe is suitably secured to said unit by the bolts 38 and nuts 39, said bolt heads being seatable in the recesses 40 provided in said shoe. The shoe also includes in its surface a plurality of 35 grooves 41 and other parallel grooves 42. These grooves are provided for the passage of the teeth 31 and 30 respectively. The teeth 30 which are in alignment with the teeth 31, of course, readily pass through the 40 deeper groove 42.

To secure greater flexibility, each of the unit plates 26 which includes a lower pivot bearing 43 pivotally supports a bolt 44 which is adapted to lie in a slot 45 in a transverse plate 46. Between the plate 46 and the head of the bolt herein indicated by the numeral 47, there is interposed a coil spring 48 for normally projecting the breaker unit into the throat of the crusher. The tension of the spring 48 is governed by the pair of locking nuts 49.

The transverse plate 46, as shown clearly in Fig. 1, is provided with a series of parallel slots 45, which slots are adapted to receive the parallel bolts 44 of the unit breaker plates. The plate 46 at each end supports an angular strap 50 which has a toothed portion 51 adapted to engage one of a plurality of teeth 52 provided in the extensions 53 of the sides 11. The bolts and nuts in-

dictated generally by the numeral 54 detachably secure said plate 46 in the adjusted position.

It will be readily apparent that to replace the breaker plate, all that is necessary is to remove the cap 22 of the desired plate and loosen the locking nuts 49 of the same plate. The bolt 44 is then removed from the slot 45 and the entire plate is removed from the crusher frame. The aforesaid arrangement of the yielding mounting of the crusher construction permits individual adjustment of each of the units of the breaker plate.

The construction of the crusher so as to provide a plurality of yieldingly supported breaker units, permits each unit to yield independently with respect to other units whenever necessary.

The invention claimed is:

1. In a crusher, the combination of a hopper having an open face, a crushing element movably mounted in the throat of the hopper, a crushing plate positioned in the hopper open face, said plate and element each comprising a plurality of substantially similar crusher forming units, said crushing element unit having a toothed periphery including a plurality of peripherally and transversely arranged rows of teeth and a plurality of other teeth of dissimilar size, said crusher element forming units being arranged relatively to each other for staggering said other teeth, and a boot detachably associated with the end of each of the crushing plate forming units, each boot including a plurality of parallel positioned grooves for the passage of the teeth on the crushing element.

2. A device of the character described in claim 1 characterized by the addition of another groove in each boot and suitably positioned for the passage of the other teeth on the movable element.

3. In a crusher of the character described, the combination of a hopper having an open face, a crushing element movably mounted in the throat of the hopper including a plurality of similar crushing units each unit including a plurality of teeth of dissimilar size, a crushing plate positioned in the hopper open face, said crusher plate including a plurality of substantially similar plate forming units, a common pivotal mounting for each of said plate forming units, individual yielding means associated with each plate forming unit, and a common support for all of said individual yielding means.

4. In a device of the character described in claim 3 and characterized by an adjustable support for said individual yielding means common support.

In witness whereof, I have hereunto affixed my signature.

EDWIN B. SMITH.
